UNITED STATES PATENT OFFICE.

CHARLES G. WELLS, OF ROCKYHILL, CONNECTICUT.

TOBACCO-STRINGING MACHINE.

971,580.

Specification of Letters Patent.

Patented Oct. 4, 1910.

Application filed December 24, 1909. Serial No. 534,787.

To all whom it may concern:

Be it known that I, CHARLES G. WELLS, a citizen of the United States, and a resident of Rockyhill, in the county of Hartford and 5 State of Connecticut, have invented a new and Improved Tobacco-Stringing Machine, of which the following is a specification.

My invention relates to the class of devices above named, and the object of the invention is to provide a device of this class 10 having novel features of advantage and utility.

One form of apparatus embodying my invention and in the use of which the objects 15 sought may be attained is illustrated in the accompanying drawings, in which—

Figure 1 is a top plan view of a device 20 embodying my invention with parts broken away to show construction and the needle being shown as near the end of its path of movement backward. Fig. 2 is a view in front elevation of the same, with parts broken away to show construction. Fig. 3 is a detail view on enlarged scale of one of 25 the leaf supporting arms. Fig. 4 is a like view of one of the clamp arms. Fig. 5 is a detail view on enlarged scale of a portion of 30 the device showing its manner of operation, the locking bolt feature being omitted as unnecessary to an understanding of the operation illustrated. Fig. 6 is a detail view on enlarged scale in section through a portion 35 of the needle carrying wheel. Fig. 7 is a detail view showing a slightly different form of construction of the clamping parts.

In the accompanying drawings the numeral 6 denotes a base constructed of any suitable material and of any desired form to properly receive the special construction 40 of apparatus which may be placed thereon. This base may be supported in any suitable manner, as shown herein it being adapted to be secured to a bench or other support, semi-permanently as by means of screws, nails 45 or the like, passed through openings 7 in the base. A crank shaft 8 having a crank handle 9 is mounted at one end of the base, a bevel pinion 10 on the crank shaft meshing with a bevel gear 11 secured to a driving 50 wheel 12 mounted with its axis arranged

vertically on the base. A needle carrying wheel 13 is also mounted with its axis vertically arranged on the base, each of these wheels having two grooves 14, one of said grooves 15 in the wheel 13 having a needle 55 groove 16 at the bottom thereof. Straps 17 are secured to each of the wheels 12, 13, a strap being located in each of said grooves 14 in each of the wheels and so arranged that when the driving wheel 12 is rotated in 60 one direction one of the straps will exert a pull upon the wheel 13 causing its rotation in an opposite direction, and the opposite strap will be pulled by the wheel 13 from the wheel 12, and in a movement of the 65 wheel 12 in the opposite direction, the action of the straps will be reversed.

A flexible needle bar 18 is mounted in the groove 16 in the wheel 13, this bar lying under one of the straps 17. The end 19 of the 70 bar is formed into a hook. In the form of construction herein shown this needle bar passes in contact with guide rollers 20 and through a slot in a guide post 21. The guide rollers are mounted upon posts 22 secured to 75 the base.

A support 23 extends from the base, in the construction herein shown this support being secured to a block 24 rising from the base. A series of leaf supporting arms 25 80 are secured to the support and arranged at suitable intervals lengthwise therealong, these arms projecting beyond the front edge of the support and having stem recesses 26. Needle openings 27 are formed through the 85 arms near their ends for the passage of the needle these openings extending into the stem recesses. Cord slots 52 extend from the ends of the bars into the needle openings 27. Clamp arms 28 are each movably supported 90 with respect to a leaf supporting arm, in the preferred form of construction and as shown herein each of these arms being pivotally mounted upon the support 23. Springs 29 hold the clamp arms against the leaf sup- 95 porting arms.

The stem recesses hereinabove described may if desired be located on the clamp arms instead of the leaf supporting arms, but in the preferred form of construction and as 100

shown herein a portion of these recesses are located on each of said arms, every alternate leaf supporting arm and every alternate clamping arm having such a recess.

5 A releasing bar 30 is mounted on the edge of the support 23 and has a sliding movement permitted by screws 31 located in slots 32 extending through the bar. The springs 29 are secured to the support 23 and exert 10 a yielding pressure upon the clamp arms sufficient to hold a leaf suspended between the two arms. Releasing pins 33 are secured to the releasing bar 30, one of these pins being located to operate upon each of the 15 clamp arms. Any suitable means for operating the releasing bar may be employed, but I prefer to operate it from a moving part of the device. A satisfactory construction for accomplishing the result is shown 20 herein in which a lever is mounted upon a pin 34 secured upon a depressed portion 35 in the block 24. This lever consists of a cam arm 36 extending underneath the rim of the wheel 13, and a nose 37 engaging a recess 38 in the bar 30. A spring 39 is employed to hold the lever in engagement with the shoulder formed by the recess 38. A cam 40 secured to the under side of the wheel 13 is located in position to operate the lever 25 30 at proper times.

In the construction herein shown each of the clamp arms has a post 41 forming its pivot, which post extends into the support 23 and the end of each bar is recessed as at 35 42 to allow passage of the needle in the operation of the device. A locking bolt 43 is mounted at the end of the support 23 in position to engage a locking recess 44 in the bar 30, a spring 45 being employed to normally hold the bolt in engagement with the 40 recess.

Brackets 46 project from the leaf supporting arm at the end of the support 23, these brackets each having a recess 47 for the reception of a cord 48 secured to the end of a lath 49.

In the operation of the machine the bolt 43 being engaged with the recess 44 in the locking bar, is first disengaged, and the 50 stems 50 of leaves are located one between each pair of arms consisting of a clamp and a leaf supporting arm, the stem of the leaf being located in the recess as shown in Fig. 5 of the drawings. The lath 49 is laid 55 across the ends of the arms 25 as shown in Fig. 5, the end of the cord 48 being placed in the recesses 47 in the brackets 46, the extreme end of the cord being located at some little distance beyond the bracket. The 60 crank handle 9 being turned to rotate the driving wheel 12 in the direction indicated by the arrow in Fig. 1, the wheel 13 is rotated in the direction also indicated by the

arrow in said figure. This causes the needle to be forced through the stems of all of the 65 leaves, passing through the needle openings 27 each of which, as shown by dotted lines in Fig. 1, is beveled as at 51 to guide the needle in its travel. When the needle reaches the end of its travel its point engages the cord 70 near its free end. By now reversing the movement of the driving wheels 12 and 13 the needle is withdrawn from the stems, in this withdrawing movement pulling the cord through all of the stems, as illustrated in 75 Fig. 5. As it withdraws from the last stem the cord also withdraws from the needle point. As the wheel 13 approaches the end of its movement, at about the position shown in Fig. 1, but moving backward, the cam 40 80 engaging the cam arm 36 moves it and the bar 30 backward until the bolt 43 shoots into the recess 44 holding the bar in this position, thus opening the clamp arms 28 and releasing the leaves, which, however, are held by 85 the cord on the lath. The end of the cord being now grasped it is passed out through the slots 52 in each of the supporting arms, carrying the leaves with it, and its free end is made fast to the end of the lath, thus 90 suspending the leaves from the cord on the lath.

It will be noted that the strap or belt 17 overlying the needle bar in the groove 16 holds said bar rigidly within the groove, 95 thus preventing buckling action of the bar that would otherwise occur by reason of the resistance to the entry of the bar into the stems, and between the first pair of arms and the wheel 13 the needle is prevented from 100 buckling by the location of the rollers 20 on opposite sides thereof. In the initial movement of the wheel 13 the cam 40 engages the lever 36 moving the nose 37 out of the recess 38 and without affecting the bar. 105

I do not limit my invention and the scope of the following claims to the devices of the foregoing illustrations and descriptions of the preferred form in which it is embodied, as these may be departed from to a greater 100 or lesser extent without avoiding the invention.

The releasing bar is shown herein as about square in cross-section, but I contemplate making this bar quite thin, and of just sufficient thickness to receive the pins 33 and provide for the recess 38.

While I have shown the needle bar as round in cross-section, I have found very satisfactory results to flow from one of a 120 rectangular shape in cross-section.

The form of the device as shown in Fig. 7 is similar to that herein shown and described with the exception that instead of mounting the springs 53 for the clamp arms 125 28 upon the support 23 these springs are

secured to the releasing bar 30. The locking bolt in this construction holds the bar with the springs 53 pressed against the arms 28, the recess in the end of the bar being arranged to permit this function and when the bar is designed for mechanical operation the parts will of course be arranged to cause engagement of the locking bolt at the proper time to exert the function above set out.

10 I claim—

1. A needle supporting wheel having a needle groove, a needle bar located within said groove and flexible to wrap about the wheel, means for rigidly holding the needle within the groove, means for supporting articles in position to be pierced by said needle, and means for rotating the wheel.

2. A needle supporting wheel having a strap groove and a needle groove, a flexible needle bar located in the needle groove, a strap located in the strap groove overlying the bar and rigidly holding it in place, means for supporting articles to be pierced by said needle, and means for exerting a pull upon said strap to rotate the needle supporting wheel.

3. A needle supporting wheel having a strap groove and a needle groove, a flexible needle bar located in the needle groove, a driving wheel supported in operative relation to the needle supporting wheel, a strap located in said strap groove overlying the needle bar and rigidly holding it in place, the end of said strap being secured to the driving wheel, means for rotating the driving wheel, and means for supporting articles to be pierced by said needle.

4. A needle supporting wheel and a driving wheel each having a pair of grooves and with a needle groove in the bottom of one of said grooves in the needle supporting wheel, a strap secured within a groove in each wheel and with its end secured in a groove in the opposite wheel, a flexible needle bar located in said needle groove underlying the strap therein, means for rotating the wheels, and means for supporting articles to be pierced by said needle.

5. A needle supporting wheel having a needle groove, a flexible needle bar located within said groove, means for rigidly holding the needle within the groove, a driving wheel supported in operative relation to the needle supporting wheel, a strap secured to both wheels to rotate the needle supporting wheel in one direction when the driving wheel is rotated, means for rotating the needle supporting wheel in the opposite direction, means for rotating the driving wheel, and means for supporting an object to be pierced by said needle.

6. A reciprocating needle bar having a pointed hooked end, means for reciprocating

the bar, means for supporting articles to be pierced by said needle, and a bracket including members spaced to receive the needle therebetween, said bracket being located adjacent to the end of the path of travel of the needle and arranged to support a cord in the path of said needle.

7. A needle bar with means for reciprocating it, means for supporting articles to be pierced by said needle, a cord supporting bracket including arms spaced apart to receive the point of the needle between them, said bracket being supported at the end of the path of travel of the needle, and said members of the bracket having recesses to receive a cord to support it in position to be engaged by the needle in its backward travel.

8. A needle supporting wheel, a flexible needle supported about the periphery of said wheel, means for supporting articles to be pierced by said needle, and means for rotating said wheel.

9. A needle supporting wheel, a flexible needle supported about the periphery of said wheel, means for supporting articles to be pierced by said needle, a strap secured to said wheel to rotate it in one direction, means for rotating the wheel in the opposite direction, and means for exerting a pull upon said strap.

10. A needle supporting wheel, a flexible needle supported about the periphery of said wheel, means for supporting articles to be pierced by said needle, a driving wheel, a strap secured to both wheels to rotate the needle supporting wheel in one direction when the driving wheel is rotated, means for rotating the needle supporting wheel in the opposite direction, and means for rotating the driving wheel.

11. A needle supporting wheel, a flexible needle bar supported by said wheel, a driving wheel, two straps secured to said wheels and arranged to rotate the needle supporting wheel in opposite directions when the driving wheel is rotated in opposite directions, means for rotating the driving wheel, and means for supporting articles to be pierced by said needle.

12. A needle supporting wheel, a flexible needle bar supported by said wheel, a driving wheel, two straps each secured to both of said wheels and extending in opposite directions on each wheel, means for rotating the driving wheel, and means for supporting an article to be pierced by said needle.

13. An article supporting arm having a passage for a needle and means to permit removal of a cord therefrom, a clamp arm movably mounted to clamp an article against said supporting arm, means for exerting pressure upon the clamp arm, means for mechanically releasing said pressure, a

reciprocating needle bar, and means for reciprocating the bar.

14. An article supporting arm having a passage for a needle and means to permit removal of a cord, an arm movably mounted and arranged to clamp an article against said supporting arm, means for exerting pressure upon the clamp arm, a sliding bar arranged to move the clamp arm away from the supporting arm, and means for locking said bar to hold said arms separated.

15. An article supporting arm having a passage for a needle and means to permit removal of a cord, an arm movably mounted and arranged to clamp an article against said supporting arm, means for exerting pressure upon the clamp arm, a sliding bar arranged to move the clamp arm, means for locking the bar with the arms separated, and means upon a moving part of the device to move said bar.

16. An article supporting arm having a passage for a needle and means to permit removal of a cord therefrom, an arm movably mounted and a spring to exert pressure thereon, a movable member operatively connected with one of said parts, a needle bar, and means for reciprocating the needle bar.

17. An arm arranged to support an article and having a passage for a needle and means to permit removal of a cord therefrom, a clamp arm having a passage for a needle opening out at the end of the arm, means for causing pressure of the clamp arm upon the supporting arm, a reciprocating needle, and means for reciprocating the needle.

18. A set of supporting devices each including an article supporting arm and a clamp arm, one of said arms having a passage forming a guide for a needle with means to permit removal of a cord therefrom and said clamp arms being movable each independently of another, means for exerting pressure upon the clamp arms, means for simultaneously relieving said pressure from all of the article supporting arms, a reciprocating needle, and means for reciprocating the needle.

19. A set of article supporting devices each including an article supporting arm and a clamp arm, one having a guide passage for a needle and means to permit removal of a cord therefrom and said clamp arms being movable each independently of another, means for exerting pressure to clamp an article between said arms, means for simultaneously relieving the pressure from all of said devices, a reciprocating needle, and means for reciprocating the needle.

20. A set of article supporting devices each including a supporting arm and a clamp arm, one having a guide passage for a

needle and means to permit removal of a cord, means for exerting pressure upon the clamp arms, a sliding bar having means to relieve the pressure of said springs upon the article supporting arms, means for operating the bar, a reciprocating needle, and means for reciprocating the needle.

21. A set of devices for supporting articles each device including an article supporting arm and a clamp arm, one having a guide passage for a needle and means to permit removal of a cord therefrom, springs mounted to exert pressure one upon each clamp arm, a sliding bar, means for locking the bar in a position to exert force upon said arms, a reciprocating needle bar, and means for reciprocating the needle bar.

22. An article supporting arm having a passage for a needle and means to permit removal of a cord therefrom, a clamp arm, a sliding bar to coöperate with said clamp arm, a spring supported to exert pressure against the clamp arm, means for locking the bar against movement, a reciprocating needle bar, and means for reciprocating the bar.

23. An article supporting arm having a passage for a needle, an arm movably mounted and arranged to clamp an article against said supporting arm, means for exerting pressure against the clamp arm, and a sliding bar arranged to control the pressure against the clamp arm.

24. A set of devices for supporting articles each device including an article supporting arm and a clamp arm, each of said clamp arms acting independently to permit insertion of an article between the arms, a reciprocating needle bar arranged to pierce the articles held by said arms, and means for reciprocating the needle bar.

25. A set of devices for supporting articles each device including an article supporting arm and a clamp arm, means for exerting pressure upon the clamp arms, each clamp arm being movable independently to permit insertion of an article between said arms, means for simultaneously releasing the hold of all the clamp arms, a reciprocating needle bar, and means for operating said needle bar.

26. An article supporting arm having a passage for a needle, a clamp arm, a reciprocating needle bar, a member movable to reciprocate said needle bar, a slide to release the pressure of said clamp arm, and connections between said slide and movable member to actuate the former.

27. An article supporting arm having a passage for a needle, a clamp arm, means for exerting pressure upon the clamp arm, a slide supported to actuate the clamp arm, a reciprocating needle bar, a rotating member

to actuate said needle bar, and a connection between the slide and rotating member to actuate said slide.

28. A set of devices for supporting articles each device including an article supporting arm and a clamp arm, means for exerting pressure upon said clamp arms, a sliding bar arranged to actuate each of the clamp arms, a reciprocating needle bar, a 10 rotating member to reciprocate said bar, and connections between said slide and rotating member to actuate the slide.

29. A set of devices for supporting articles each device including an article sup-

porting arm and a clamp arm, means for 15 exerting pressure upon the clamp arms, a sliding bar supported to actuate the clamp arms, a needle supporting wheel, a flexible needle supported upon the periphery of said wheel, means for rotating the wheel to cause 20 the needle to pierce articles held by said arms, and connections between said wheel and sliding bar to actuate the latter.
